SEWING MACHINE

Otto R. Haas, North Beverly, Mass., assignor to
 United Shoe Machinery Corporation, Borough
 of Flemington, N. J.

Application October 20, 1939, Serial No. 300,444

7 Claims. (Cl. 112—227)

The present invention relates to curved needle wax thread shoe sewing machines, and more particularly to improvements in needle guiding devices for a lockstitch machine of the type illustrated and described in U. S. Letters Patent to present inventor, No. 2,148,197 of February 21, 1939 and co-pending application Serial No. 118,622 filed December 31, 1936 of which application the present application is a division.

10 The objects of the present invention are to provide means in a curved needle sewing machine for reinforcing the needle against the strains incident to sewing operations, and to improve the construction of such machines so that needles of smaller gage than heretofore considered possible may be used with the heavy type of work ordinarily sewn by machines of this nature.

With these and other objects in view, one feature of the invention relates to the provision in a curved needle sewing machine having a stud about which the needle oscillates, of a plurality of relatively movable needle guides on the stud so arranged that the needle is supported at a number of separated points along its length. As hereinafter described, means are provided for moving the guides with the needle until the needle engages the work and thereafter for causing the guides to be moved towards each other as the needle enters the work. Preferably, the guides are actuated at least in part by yielding means and, when so actuated, it is possible to move the guides with the needle by frictional engagement with the needle supporting segment. These and other features of the invention including certain novel and improved constructions and arrangements of parts will be readily understood by one skilled in the art from the following description taken in connection with the accompanying drawings, and will be more particularly pointed out in the appended claims.

In the drawings Figure 1 is a view in vertical section, illustrating parts of a machine embodying the present invention; Figures 2 and 3 are detail side views on an enlarged scale, partly in section, illustrating the needle and needle guides of the machine shown in Figure 1, in successive operating positions; and Figure 4 is a view in front elevation and in section of the needle and awl supporting stud of the machine.

The stitch-forming and work-feeding devices of the machine are best illustrated in Figure 1, and include a curved hook needle 10, a curved awl 12, a rotating shuttle or loop taker 14

within a guideway of which is mounted a hollow circular thread case 16 containing a supply of locking thread, a looper 18, a thread hook or finger 20, a take-up 22, a presser-foot 24, and a work support 26. The mechanisms for actuating these devices are driven from the main sewing shaft 27 and are not illustrated in detail since they form no part of the present invention except as hereinafter described. These mechanisms are substantially the same as those disclosed in the present inventor's prior U. S. Letters Patent and application above referred to.

In previous curved needle sewing machines, it has been the practice to employ a needle of sufficiently heavy gauge to prevent bending while in engagement with the work, an awl of corresponding size or slightly larger being required. Where stitches of very short length are being inserted, the work may be broken up by the awl perforations and become weakened unduly along the seam line. In order to avoid such weakening, it is usual to reduce the sizes of the needle and awl, but when this is done, frequent breakage of the needle may result.

To enable a smaller needle than ordinary to be used so that the needle may enter a relatively small awl perforation in the work and may be retracted with a heavy thread without bending or breaking, according to the present invention, there is mounted on the needle supporting stud, indicated at 28 in Figures 2 and 4, a pair of needle guides 30 and 32, movable relatively to each other along the needle as the needle enters or retracts from the work. The needle is mounted in a segment 34 on the needle stud 28 and a reduced portion of the hub of the needle segment provides a bearing for the needle guide 30, which engages the needle at intermediate point along the length of the needle. The hub of the needle guide 30 is provided with an outer bearing surface on which the needle guide 32 is mounted and arranged to engage and cover the needle near its hooked end. When the needle enters the work, the needle guide 32 moves with the needle until stopped by the presser-foot 24, the needle continuing through the work.

To move the needle guide 32 with the needle, the guide is provided with a yieldingly actuated friction shoe 36 engaging a concentric surface on the needle segment 34 and an arm 38 having a lug adapted to cooperate with an abutment shoulder 40 on the needle segment. In order to hold the needle guide from movement until the needle is clear of the work, the arm 38 is engaged by an enlargement 42 on the thread finger

20. After the needle loop has been removed from the needle, the thread finger imparts a further movement to the needle guide 32 to cause it to cover the empty hook of the needle, the arm 5 38 engaging shoulder 40 and preventing movement of the guide beyond the end of the needle, as described more fully in inventor's U. S. Patent No. 2,038,282 of April 21, 1936.

To separate the needle guides 30 and 32 and hold them in spaced relation along the needle, the intermediate guide 30 is formed with a bore 44 to receive a compression spring 46 acting between the end of the bore 44 and a pin 48 on the needle guide 32. To limit the movement of 10 the guides away from each other, the intermediate guide 30 is formed with a projection 50 co-operating with a portion of the guide 32. When the needle is moved towards the work, the hook covering guide 32 engages the presser-foot, which 15 holds the guide 32 stationary as the needle enters the work. Both guides then remain stationary until the needle segment engages the intermediate guide 30. The spring 46 is then compressed and the intermediate guide is moved towards the 20 hook covering guide 32 to the position shown in Fig. 3, until the needle reaches the limit of its penetrating stroke. When the needle is retracted from the work reverse movements take place, the intermediate guide moving with the needle 25 segment until the projection 50 engages the guide 32. The guide 32 then moves with the guide 30 and the friction of the shoe 36 on the needle segment is sufficient to carry the guides with the needle until the guide 32 is engaged by the 30 thread finger. The two guides are then moved further towards the hooked end of the needle until the guide 32 is actuated to cover the empty needle hook, as previously described.

The nature and scope of the invention having 35 been indicated, and a construction embodying the several features of the invention having been specifically described, what is claimed is:

1. A sewing machine having, in combination, 40 stitch forming devices comprising a curved hook needle, a stud about which the needle oscillates, and a plurality of needle guides on the stud arranged for movement relatively to each other along the needle as the needle enters the work.

2. A sewing machine having, in combination, 45 stitch forming devices comprising a curved hook needle, a stud about which the needle oscillates, a plurality of relatively movable needle guides on the stud arranged to support the needle at separated points, and means for moving the 50 guides with the needle until the needle engages the work, and thereafter for causing the guides to be moved towards each other as the needle enters the work.

3. A sewing machine having, in combination,

5 stitch forming devices comprising a curved hooked needle, a stud, a needle segment, in which the needle is secured, mounted on the stud, a plurality of relatively movable needle guides on the stud, and yielding means for maintaining the guides in separated relation while the needle is disengaged from the work.

4. A sewing machine having, in combination, 10 stitch forming devices comprising a curved hooked needle, a stud, a needle segment in which the needle is secured mounted on the stud, a plurality of relatively movable needle guides on the stud, means for driving one of the guides frictionally from the needle segment, and yielding means for maintaining the needle guides in separated relation while the needle is disengaged from the work.

5. A sewing machine having, in combination, 15 stitch forming devices comprising a curved hooked needle, a stud, a needle segment in which 20 the needle is secured mounted on the stud, a plurality of relatively movable needle guides on the stud, yielding means for maintaining the guides in separated relation when the needle is disengaged from the work, and interengaging 25 portions on the guides for limiting their movement away from each other.

6. A sewing machine having, in combination, 30 stitch forming devices comprising a curved hooked needle, a stud, a needle segment in which 35 the needle is secured mounted on the stud, a plurality of relatively movable needle guides on the stud, yielding means for maintaining the guides in separated relation when the needle is disengaged from the work, interengaging portions 40 on the guides for limiting their movement away from each other, and a shoulder on the needle segment for preventing movement of the guides beyond the end of the needle.

7. A sewing machine having, in combination, 45 stitch forming devices comprising a curved hook needle, a stud, a needle segment on the stud, a needle guide arranged to cover the hook of the needle, a second needle guide arranged to move along the needle relatively to and between the 50 hook covering guide and the needle segment, and means for actuating said guides comprising yielding means acting to separate the guides, interengaging portions on the guides for limiting their movement away from each other, a shoulder on the needle segment for preventing movement of the guides beyond the point of the needle, and a friction shoe engaging the needle segment for moving the hook covering needle guide as the threaded needle is being withdrawn from 55 the work to prevent said guide from covering the needle hook before the loop of needle thread has been taken therefrom.

OTTO R. HAAS.
